UNITED STATES PATENT OFFICE.

ALBERT PANCOAST, OF DETROIT, MICHIGAN, ASSIGNOR TO AMERICAN CAR AND FOUNDRY COMPANY, OF ST. LOUIS, MISSOURI, A CORPORATION OF NEW JERSEY.

CAR-BOLSTER.

SPECIFICATION forming part of Letters Patent No. 715,416, dated December 9, 1902.

Application filed August 17, 1901. Serial No. 72,335. (No model.)

To all whom it may concern:

Be it known that I, ALBERT PANCOAST, a citizen of the United States, residing at Detroit, Michigan, have invented a certain new and useful Improvement in Car-Bolsters, of which the following is a full, clear, and exact description, such as will enable others skilled in the art to which it appertains to make and use the same, reference being had to the accompanying drawings, forming part of this specification, in which—

Figure 1 is a side elevational view of my improved bolster, one end thereof being shown in section. Fig. 2 is a plan view of the bolster, the left-hand end being a top plan view and the right-hand end an inverted or bottom plan view. Fig. 3 is a vertical cross-sectional view on line 3 3 of Fig. 1.

This invention relates to a new and useful improvement in bolsters designed especially for use in car construction, and while I have shown my improvement embodied in the form of a truck-bolster it is obvious that with slight changes it could also be used to advantage as a body-bolster.

The objects of this present invention are to enable the use of a machine-riveter in the assemblage of the principal members and also to use commercially-rolled or structural steel as said principal members, arranging them in such manner that a simple, strong, and cheap bolster is produced.

With these objects in view the invention consists in the construction, arrangement, and combination of the several parts, all as will hereinafter be described and afterward pointed out in the claims.

In the drawings, 1 indicates the side web-plates, which are preferably provided with integral laterally-presented flanges 2 along their upper edges. These flanges, as shown in Figs. 1 and 2, do not extend to the ends of the web-plates, but terminate within the lines of the truck column-guides.

3 indicates the top cover-plate, preferably coextensive in length with the flanges 2, to which it is riveted.

4 indicates the center-bearing, which is riveted in position, as usual. Side bearings (not shown) are also provided.

5 indicates a reinforcing-bracket, preferably a malleable casting, provided with a vertical opening 6 for the reception of the king-pin. This bracket is riveted to the top plate (and also the center-bearing) and to the side plates. 55

7 indicates a channel whose flanges are presented downwardly and riveted to the lower edges of the side plates.

8 indicates column-guides, preferably in the form of angles or castings, secured to the side plates near the ends of the bolster.

It will be observed that the side plates have their lower edges at the ends of the bolster substantially parallel with their upper edges for a short distance and that the middle portion of the bolster is considerably deeper than these end portions; also, that the channel 7 is bent to the shape of the lower edges of the side plates. By this construction the ends of the channel afford spring-seats for the bolster-supporting springs, (see Fig. 1,) and at the same time said channel serves as a tension member, the inclined portions thereof lying in the planes of the greatest strains. 65 70

The bolster as an entirety observes generally a box-girder form of variable depth, the ends of the bolster being substantially U-shaped, due to the termination of the cover-plate at the column-guides, as shown in Fig. 1. This cover-plate under load is placed in compression, as are also the flanges 2, to which it is attached. 75

Flanged plates or castings 10 are preferably arranged at the ends of the bolster opposite the column-guides, as shown in Figs. 1 and 85 2, for the purpose of stiffening same, so that stresses may be transmitted from the side webs to the channel. These castings or plates 10 are riveted to the channel.

I am aware that many minor changes in the construction, arrangement, and combination of the several parts of my device can be made and substituted for those herein shown and described without in the least departing from the nature and principle of my invention. 90 95

Having thus described my invention, what I claim, and desire to secure by Letters Patent of the United States, is—

1. A bolster comprising side web-plates, the upper edges of which terminate in laterally- 100

- projecting flanges, a cover-plate attached to said flanges and resting thereon, a channel between the lower edges of the side web-plates, said channel being provided with 5 downwardly-projecting flanges riveted thereto and extending to the end of the bolster, and a brace connected thereto and to the web-plates above said channel; substantially as described.
- 10 2. A bolster comprising side web-plates provided with laterally-presented flanges along their upper edges, which flanges terminate short of the ends thereof, a cover-plate attached to said flanges, and being coextensive 15 in length therewith, and a channel between the lower edges of the side web-plates the flange thereof extending downwardly from the web portion thereof; substantially as described.
- 20 3. A box-girder bolster of variable depth, the same comprising side web-plates, laterally-presented flanges along one edge of each of said web-plates, a channel which is bent to conform to the contour of the opposite edges 25 of said web-plates the web thereof lying above the line of said edges, and a center-bearing and side bearings carried by said bolster; substantially as described.
4. A bolster, consisting of web-plates of variable depth, the upper edges of said web-plates terminating in laterally-projecting flanges, a cover-plate forming a compression member riveted to said flanges, a channel 30 whose flanges are presented downwardly and riveted to the lower edges of the web-plates, said channel being bent to follow the line of the lower edges of the web-plates, the ends of said channel lying in substantially the same horizontal plane, to provide spring- 35 seats, and column-guides attached to the web-plates; substantially as described.
5. A bolster comprising side web-plates provided with outwardly-presented flanges along their upper edges, a cover-plate attached to said flanges, a channel between the lower 45 edges of the web-plates, and stiffening-braces 10 attached to the end of the web-plates and the ends of the channel; substantially as described.
6. A box-girder bolster having web-plates 50 with lateral flanges, a cover-plate thereon projecting over said flanges, a tension member within the lower portion of the web-plates and having downwardly-projecting flanges connected to said web-plates, all of said 55 flanges extending outwardly from said bolster to permit connection thereof by means of a machine-riveter; substantially as described.
7. A box-girder bolster comprising a compression member, tension member and web-plates, whose tension member projects beyond the compression member, the projecting ends of the tension member providing spring-seats, and braces above said seats uniting the tension member and said web-plates; substantially 60 as described.
8. A box-girder bolster comprising a compression member, web-plates with lateral flanges connected thereto, and a tension member between said web-plates, with flanges extending downwardly and all of said flanges presented outwardly to permit the union thereof by means of a machine-riveter; substantially as described. 70
- In testimony whereof I hereunto affix my signature, in the presence of two witnesses, this 12th day of August, 1901.
- 75 ALBERT PANCOAST.
